UNITED STATES PATENT OFFICE.

LOUIS F. JACKSON, OF CHEBANSE, ILLINOIS.

GRAIN DOOR.

Application filed November 20, 1924. Serial No. 751,117

To all whom it may concern:

Be it known that I, LOUIS F. JACKSON, a citizen of the United States, residing at Chebanse, in the county of Iroquois and State of Illinois, have invented certain new and useful Improvements in Grain Doors, of which the following is a specification.

This invention relates to doors for use on grain carrying railroad cars, granaries, and the like, and aims to provide a novel and improved door of this character, which can be conveniently and efficiently opened and closed when desired, and being of such a construction that when closed the same will form a grain tight closure for the car or the like.

Another object of the invention is to provide a pair of doors, each constructed of a series of hingedly connected metallic sections arranged to be wound upon drums positioned adjacent the door opening, one of said doors being on the inside to serve as a grain tight closure, while the other door is on the outside for preventing water or any other foreign matter from gaining access to the inside door and consequently to the interior of the car, said drums having means for rotating the same to open or close either of said doors.

It is also an object of the invention to provide a grain door of the kind indicated, which is substantial in construction, which can be manufactured economically, and which will be thoroughly efficient and practical in use.

With the foregoing and other objects in view, which will be apparent as the description proceeds, the invention resides in the construction and arrangement of parts, as hereinafter described and claimed, it being understood that changes can be made within the scope of what is claimed without departing from the spirit of the invention.

The invention is illustrated in the accompanying drawings, wherein:

Figure 1 is a fragmentary vertical sectional view through a railroad car showing my improved door applied thereto,

Figure 2 is a view taken on line 2-2 of Figure 1,

Figure 3 is a vertical section on line 3-3 of Figure 2,

Figure 4 is a section on line 4-4 of Figure 1,

Figure 5 is a horizontal section on line 5-5 of Figure 1,

Figure 6 is a section on line 6-6 of Figure 1,

Figure 7 is a section taken on line 7-7 of Figure 3, and

Figure 8 is a section on line 8-8 of Figure 7.

In carrying out the invention, the numeral 10 designates a side wall of a railroad grain car, which has an opening 11 therein about which my improved grain door is applied, while the numerals 12 and 13 indicate the floor and roof of the car respectively.

Arranged to slide on each side of the wall 10 adjacent the opening 11 is a pair of doors, each constructed of a series of hingedly connected metallic sections, the door 14 outside of the wall 10 and the door 15 on the inside. Each section of each door has a lug or projection 16 extending from each end thereof to slide in channel members that form guides, said channel members being secured to the wall 10 at each side of the opening 11. The numerals 17 and 18 indicate the guides that are positioned on the outside of the wall 10 while the numerals 19 and 20 designate the channel guide members that are arranged on the inside of the wall for the inside door 15.

The channel shaped guide members each have a flange 21 extending from one side and the entire length thereof through which bolts 22 extend for attaching the guides to the wall 10, said channel shaped guides also having inwardly directed flanges 23 at the open side thereof which engage with the lugs or projections 16 when the same extend into the channel of the guides. The metallic sections which form the doors each have at their lower horizontal edge an enlarged portion to provide a cylindrical shaped channel 24 that receives the elongated curved head 25 on the upper horizontal edge of the section therebeneath. Each of the sections is slightly curved or bowed outwardly throughout the major portion thereof, as at 26, for a purpose hereinafter more fully described.

The lower ends of the doors 14 and 15 each have a bumper 27 attached thereto for engaging the floor 12 when the doors are lowered and for limiting the upward move-

ment of the doors 14 and 15.

ment of the doors to prevent the same from being slid entirely out of the guides, as the bumpers 27 project slightly further into the guides than the projections 16 so as to 5 engage stops 28, clearly shown in Figure 7 of the drawings.

The upper end of each door is wound upon a drum, the door 14 on the drum 29 above the roof 13 of the car, and the door 10 15 on the drum 30 positioned in the roof construction of the car. The doors 14 and 15 are arranged to pass over the drums upon which the same are to be wound and then around drums 31 and 32 respectively in the rear of the first mentioned drums, before returning to said first mentioned drums. The curved elongated head 25 of the first section of each of the doors is received in the drums 29 and 20 30 by passing through longitudinal slots 33 therein. It will be noted that when the drums 29 and 30 are rotated in a clockwise direction the doors 14 and 15 respectively will be drawn upwardly and wound thereon after passing around the drums 31 and 32 respectively.

The drums 29, 30, 31, and 32, are mounted upon shafts 34, 35, 36, and 37 respectively, which have their opposite ends attached to 30 supporting members 38. The members 38 that support the drums 29 and 31 are secured to a slightly inclined plate 39 positioned upon the roof of the car, while the supports for the drums 30 and 32 are attached to the opposite side of a metallic frame 40 secured to the underside of the roof 13. At each end of each drum is a sprocket 41 which is secured thereto by a key or the like. The sprockets on each end 40 of the drum 29 are connected by chains 42 and 43 to the sprockets on the drum 31 in rear thereof, and the sprockets on the drum 30 are connected in a similar manner to the sprockets on the drum 32 by sprocket 45 chains 44 and 45, so that when the drums 29 and 30 are rotated, the drums 31 and 32 respectively will be rotated in the same direction and at the same speed, which will cause the winding of the door 14 on the 50 drum 29 and the door 15 on the drum 30.

The drum 29 is slightly longer than the remaining drums and has another sprocket 46 thereon and secured thereto from which a sprocket chain 47 extends to a sprocket 48 carried by the shaft 35. The sprocket 48 is loose on the shaft 35 and has a clutch face 49 on one side thereof for engaging a like clutch face 50 carried by a worm gear 51 which is also carried by the shaft 35, 55 said worm gear having means connected therewith for rotating the same, which means will be described in detail as the description proceeds. The opposite side of the sprocket 48 has an annular recess 52 therein which receives an annular flange 53

carried at one end of a collar 54 slidable on the shaft 35 but fixed thereto against rotation. The flange 53 is positioned in the recess 52 for rotary movement yet retained therein by a ring member 55 secured to 70 the sprocket 48. The collar 54 has a clutch face 56 arranged to engage a similar clutch face 57 provided on one end of the drum 30. An annular groove 58 is provided in the collar 54 which receives inwardly directed pins 59 carried by a yoke 60 on one end of a slidably mounted L-shaped lever 61. It will be noted that when the lever 61 is shifted to engage the clutch faces 49 and 50, the worm gear 51 will rotate the 80 drums 29 and 31 due to the sprockets 46 and 48 and sprocket chain 47, and that when the clutch faces 56 and 57 are engaged the drums 30 and 32 will be rotated as the worm gear 51 rotates the shaft 35 which will rotate the collar 54 upon which the clutch face 56 is arranged.

In order to rotate the worm gear 51 a worm 62 carried by a shaft 63 meshes with said worm gear, said shaft having a bearing 64 for one end thereof mounted on one of the supports 38, while the opposite end of the shaft 63 passes through a bearing 65 and opening 66 carried by and extending through the wall 10 respectively. Attached to the last mentioned end of the shaft 63 is a pair of universal joints 67 which are in turn connected to a vertical shaft 68 mounted for rotation in a bearing 69 carried by the wall 10. The lower end of the shaft 68 is received in a casing 70 arranged adjacent the floor 12 of the car, and has a beveled gear 71 thereon which meshes with a like gear 72 carried by a bearing member 73 through which the shaft 68 extends. Secured to the gear 72 is a crank handle 74 for transmitting rotary movement to the beveled gears 72 and 71 through the shafts 68 and 63 and to the worm gear 51. The casing 70 has a slot 75 therein, while the member 73 is rotatable on the shaft 68 so that the handle 74 may be swung away from the wall 10 when it is desired to rotate the drums for raising or lowering the door 14 or door 15.

To prevent unauthorized persons from opening the doors, a keeper 76 is secured to the wall 10 by bolts, rivets, or the like, said keeper having a pair of parallel spaced lugs 77 projecting therefrom between which the crank handle 74 is received when it is desired to lock same against operation. A headed pin 78 is then passed through a pair of aligning openings, one in each projection, and a sealing device 79, such as that commonly used for sealing railroad cars, is passed through an opening in the lower end of the pin.

The lower end of the L-shaped lever 61 projects through a slot 81 in the wall 10,

and is slidably mounted in a pair of eyes 82 carried by the wall. To shift the lever 61 in the eyes 82 a crank arm 83 is pivotally connected to the wall 10 by an eye 84 and 5 a bearing member 85, the crank of said arm being adapted to engage a pair of pins 86 carried by the lever 61, one of said pins on each side of the crank. The lower end of the crank arm extends downwardly to- 10 wards the floor of the car and is bent at right angles, as at 87, to provide a handle for turning the crank to complete a driving connection to certain of the drums for operating either of the doors.

45 One of the metallic sections forming a part of the inside door 15 has the center portion thereof cut away to provide an opening in said door for permitting a grain spout to extend therethrough for loading the car, said cut away portion being clearly illustrated by the numeral 88 in Figures 7 and 8 of the drawings. To prevent the two separate portions 89 and 90 of this section from sliding sideways with relation to the 25 other section, the lugs 16 thereon have their ends provided with extensions 91 engaging the inner sides of the small inwardly directed flanges 23 of the channel shaped guides.

30 Should it be desired to replace one of the sections in either of the doors 14 and 15, due to a section breaking or becoming worn, one of the channel guides for each door has a short removable portion at its upper end, 35 as at 92, the lower end of which is adapted to overlap the remainder of the guide, as indicated by the numeral 93, said portion when removed will permit the sliding of one section at a time from a door.

40 Positioned about the drums and sprockets for the outside door 14 is a hood 94 having an extension 95 thereon projecting downwardly and over the universal joint 67, said hood also having a pair of closure lids 96 and 97 hingedly connected thereto as at 98, to permit the lids to be raised when desired.

A handle 99 is attached to the lower section of the outside door 14 which can be engaged to lower the door in order to close 50 the same, while a like handle 100 is attached to the inside door 15 for a similar purpose.

In operation of my improved device, when the doors are closed and the car is loaded, and it is desired to raise the doors and un- 55 load the car, the handle 87 of the crank arm 83 is turned to the right, shifting the sprocket 48 and causing the engaging of the clutch face 49 thereon with the clutch face 50 on the worm gear 51. The seal 79 is then 60 broken and the pin 78 removed which permits the handle 74 to be swung away from the wall 10 of the car, after which the crank handle 74 is turned, rotating the shafts 68 and 63, causing rotary movement to be im- 65 parted to the worm gear 51 through which

the sprockets 48 and 46 rotate the drums 29 and 31 which will draw the outside door 14 upwardly, winding the same on the drum 29. After the door 14 is entirely raised, the handle 87 is turned in the opposite direction 70 or to the left, which will engage the clutch face 57 on the drum 30 with the clutch face 56 on the collar 54, so that further turning movement of the handle 74 will cause the drums 30 and 32 to rotate and raise the inside door 15, as the worm gear 51 and the collar 54 having the clutch face 56 both turn together with the shaft 35.

When it is desired to lower the doors, the handle 74 is turned in the opposite direction, 80 after the various clutch faces have been engaged by the turning of the handle 87. The handles 99 and 100 are attached to the doors to permit the same to be pulled down should the same tend to bind or stick when lowering the same.

Having thus described my invention, what I claim as new is:

1. A device of the character described, comprising a pair of doors adapted to lie side by side for closing a single opening, each composed of a series of hingedly connected sections, guide members for supporting said doors in an operative position, and means for raising or lowering either door independent of the other.

2. A device of the character described, comprising a pair of doors adapted to lie side by side for closing a single opening, each composed of a series of hingedly connected sections, guide members for supporting the doors in an operative position, rotatable drums arranged for winding said doors thereupon, and means operatively connected to said drums for raising or lowering either of said doors.

3. A device of the character described, comprising a pair of doors each composed of a series of hingedly connected sections, guide members for supporting said doors in an operative position, a pair of drums arranged for winding said doors thereupon, a second pair of drums one arranged in rear of each of said first mentioned drums, said doors arranged to pass over said second mentioned drums when the same are raised or lowered, and means for rotating said first mentioned drums independent of each other.

4. A device of the character described, comprising a pair of doors each composed of a series of hingedly connected sections, guide members for supporting said doors in an operative position, a pair of drums arranged for winding said doors thereupon, a second pair of drums one arranged in rear of each of said first mentioned drums, the upper ends of said doors being arranged to pass over said first mentioned drums around said second mentioned drums and having their

upper extremities attached to said first mentioned drums, and means operatively attached to said first mentioned drums for imparting rotary movement thereto.

5. A device of the character described, comprising a pair of doors each composed of a series of hingedly connected sections, guide members for supporting said doors in an operative position, a pair of drums arranged for winding said doors thereon, a second pair of drums one arranged in rear of each of said first mentioned drums, the upper ends of said doors being arranged to pass over said first mentioned drums around said second mentioned drums and having their upper extremities attached to said first mentioned drums, means operatively connecting each of said first mentioned drums with the second mentioned drums in rear thereof, and means for imparting rotary movement to either of said first mentioned drums independent of the other.

6. A device of the character described, comprising a pair of doors each composed of a series of hingedly connected sections, guide members for supporting the lower ends of said doors when the same are in a lowered or closed position, a pair of drums each arranged for winding one of said doors thereupon, a second pair of drums one arranged in rear of each of said first mentioned pair, sprockets arranged upon the opposite ends of each drum, sprocket chains connecting the sprockets of each of said first mentioned drums with the sprockets of the second mentioned drums in rear thereof, said doors having the upper ends thereof passing over said first mentioned drums and about said second mentioned drums and having their upper extremities attached to said first mentioned drums, a clutch means arranged for attachment with either of said first mentioned drums, and means for imparting a rotary movement to the drums engaged by said clutch member.

7. A device of the character described, comprising a pair of doors each composed of a series of hingedly connected sections, guide members arranged for supporting the lower ends of said doors in an operative position when the same are closed, a pair of drums each arranged for winding one of said doors thereupon, means for imparting rotary movement to either of said drums, and a clutch member arranged for engaging either of said drums with said operating means.

8. A device of the character described, comprising a pair of doors each composed of a series of hingedly connected sections, guide members arranged for supporting the lower ends of said doors in an operative position when the same are closed, a pair of drums each arranged for winding one of said doors thereupon, a manually operated

vertical shaft arranged to rotate either of said drums, a crank handle operatively connected to said vertical shaft for rotating the same, and means engaging said crank handle for holding the same against operation. 70

9. A device of the character described, comprising a pair of doors each composed of a series of hingedly connected sections, guide members arranged for supporting the lower ends of said doors in an operative position 75 when the same are closed, a pair of drums each arranged for winding one of said doors thereupon, a manually operated vertical shaft arranged to rotate either of said drums, a casing arranged about the lower 80 end of said shaft, a crank handle carried by said casing, beveled gears connecting said crank handle with said shaft, and means for permitting said crank handle to be swung partially about said shaft when it is 85 desired to operate the same.

10. A device of the character described, comprising a pair of doors each composed of a series of hingedly connected sections, guide members arranged for supporting the lower 90 ends of said doors in an operative position when the same are closed, a pair of drums each arranged for winding one of said doors thereupon, a manually operated vertical shaft arranged to rotate either of said 95 drums, a casing arranged about the lower end of said shaft, a crank handle carried by said casing, beveled gears connecting said crank handle with said shaft, means for permitting said crank handle to be swung partially about said shaft when it is desired to operate the same, and means for holding said crank handle in an inoperative position when 100 desired.

11. A device of the character described, 105 comprising a door composed of a series of hingedly connected sections, guide members arranged upon the opposite sides of said sections when the same are in a closed position for preventing end movement of any of the 110 sections with relation to each other, a removable portion on one of said guide sections for permitting the replacement of one of the sections when desired.

12. A device of the character described, 115 comprising a pair of doors adapted to lie side by side for closing a single opening each composed of a series of hingedly connected sections, drums for winding said doors thereupon, one of the sections of one 120 of said doors having an opening therein, and means attached to said drums for rotating the same independent of each other.

13. A device of the character described, 125 comprising a pair of doors composed of hingedly connected sections, lugs projecting from the opposite ends of said sections, channel shaped guide members arranged upon the opposite ends of each section when in a lowered position and receiving the lugs 130

thereon, one of the sections of one of the doors having a portion thereof intermediate its ends removed to provide an opening, side extensions upon the opposite side of 5 said lugs of said section having the opening therein, and inwardly directed flanges formed on said channel shaped guide members and engaged by said extensions for preventing sliding or end movement of said 10 section having the central portion thereof removed.

14. A device of the character described, comprising a pair of flexible doors, guide members for supporting the doors in an operative position, a pair of drums arranged 15 for winding said doors thereupon, power supplying means, a sliding clutch arranged for connecting said power supplying means with either of said drums, a slideable arm ar-

ranged for sliding said clutch, and a lever 20 attached to said slideable arm to shift the same to slide said clutch.

15. A device of the character described, comprising a pair of flexible doors, guide members for supporting the doors in an operative position, a pair of drums arranged for winding said doors thereupon, power supplying means, a sliding clutch arranged for connecting said power supplying means with either of said drums, a movable arm 25 30 arranged to slide said clutch, and a crank lever to operate the same to slide the clutch.

In testimony whereof, I have affixed my signature in the presence of two witnesses.

LOUIS F. JACKSON.
